BEDPAN

Joseph H. Botenstein, Chicago, Ill.

Application July 11, 1940, Serial No. 344,970

4 Claims. (Cl. 4—112)

This invention relates to bed pan urinals particularly adapted for men.

One object of this invention is to provide a means whereby a patient confined to bed may alternately evacuate the bowels and urinate, thereby preventing withholding either while seated on the bed pan.

Another object of the invention is to provide a urinal attachment to bed pans of a particular design capable of longitudinal adjustment to suit the individual patient and clamping means to insure the adjustment of the urinal.

A further object of the invention is to provide a detachably connected urinal which may easily be sterilized and applied after its periodical use.

A still further object of the invention is to provide apparatus of the above described character which will be formed of a few strong simple and durable parts, which will be inexpensive to manufacture and which will not easily get out of order.

With the above and other objects in view, the invention consists of certain novel details of construction and combination of parts herein-after fully described and claimed, it being understood that various modifications may be resorted to within the scope of the appended claims and without departing from the spirit or sacrificing any of the advantages of the invention.

In the accompanying drawing forming a part of this invention.

Figure 1 is a perspective view of the invention shown associated with a bed pan.

Figure 2 is a perspective view of a pair of gripping members.

Figure 3 is a perspective view of the invention.

Referring now to the drawing in which like characters of reference designate similar parts in the various views, 10 designates a bed pan having a rectangular opening within the top wall thereof disposed to extend from the forward end wall rearwardly past the transverse median line of the bed pan, and 11 a urinal detachably connected to the bed pan 10 extended laterally across the rectangular opening.

A plate 12, rectangular in plan, is rolled on itself at one of the sides thereof to form a tubular guide member 13 disposed to underlie the plate 12. An elongated longitudinally channelled strip 14 of sheet metal or the like is secured to the under side of the plate 12, intermediate of and parallel in relation to the sides of the plate 12. The channel strip upon its application to the plate 12 provides a second guide member. A pair of U-shaped members 15 and 16 prefer-

ably formed of wire each comprise arm portions 17 and 18 and an integral connecting base portion 19 and 20. The arm portions are bent laterally intermediate of their length to form jaw portions 21 and 22 disposed at an angle to the arm portions as best shown in Figure 2 of the drawing.

The free extremities of the arm portions 17 and 18 of the members 15 and 16 are extended, one extremity of each, into the channel of the strip 14 and into the longitudinal bore of the guide member 13. The arm portions 17 and 18 of the members 15 and 16 are slidably associated with and frictionally held within the guide members 13 and 14 for adjustment of the jaw portions 21 and 22 to and away from one another.

The plate 12 is placed laterally on the bed pan 10 across the rectangular opening to dispose the arm portions 17 and 18 to rest on the top wall of the bed pan 10 to dispose the jaw portions 21 and 22 to depend adjacent the side walls of the bed pan 10. Upon movement of the jaw portions 21 and 22 toward one another, the sides of the bed pan are gripped between the jaw portions 21 and 22 at successive points throughout the length of the bed pan 10 for longitudinal adjustment of the plate 12 at any desired location above the rectangular opening in the bed pan 10.

A conical urinal tube 23 is fixed to and extends through the plate 12 at an inclination toward the forward end of the bed pan 10 as shown in Figure 1, and terminates below the plate 12 in an elbow 24 directed downwardly and adjacent the bottom of the bed pan 10 as more clearly shown in Figure 2. For application the urinal 11 is placed on the top wall of the bed pan 10 as shown in Figure 1 and is adjusted longitudinally thereon, to suit the requirements of the individual patient, and is clamped at the longitudinal adjustment by the engagement of the jaw portions 21 and 22 on the side walls of the bed pan 10.

What I claim is:

1. A urinal for bed pans comprising a rectangular plate having parallel spaced longitudinally disposed tubular guides, a pair of U-shaped members slidably mounted within the guides at respective ends of the plate, said members bent laterally providing clamping jaws on the outer ends of the members, and a tubular means conducting urine through the plate.

2. A urinal attachment for bed pans comprising a plate, a pair of jaw members being carried

by opposite ends of the plate and adapted for adjustment to and away from one another, and a conical urine tube extending through the plate at an angle having an inclination toward one side of the plate and terminating below the plate 5 at substantially right angles to the plate.

3. A device of the character described comprising a plate having longitudinal guides, a pair of supporting U-shaped members frictionally received within said guides disposed at opposite ends of the plate, said members bent adjacent the base thereof forming gripping jaws adapted to travel to and away from one another, and a flared urine conducting means extending through said plate.

4. A urinal for attachment for a bed pan comprising a rectangular plate of sheet material

being rolled at one longitudinal edge forming a tubular guide and having an opening, a longitudinally grooved strip underlying and secured to the plate in parallel spaced relation to the rolled edge forming a second guide, a pair of substantially U-shaped clamp members slidably associated with the ends of the plate and frictionally received within the guide members at opposite ends of the plate, said clamp members being bent laterally adjacent the base portion thereof forming gripping jaws slidably adjusted to and away from one another, and a conical urinal tube extending through the opening plate and terminating in an elbow depending and directed from the plate.

JOSEPH H. BOTENSTEIN.
